UNITED STATES PATENT OFFICE.

CHARLES WEIS, OF LANSDALE, PENNSYLVANIA, ASSIGNOR OF TWO-THIRDS TO HARVEY B. LUTZ AND HARRY M. COHN, BOTH OF LANCASTER, PENNSYLVANIA.

MAIL BOX

Application filed May 12, 1922, Serial No. 560,396.

To all whom it may concern:

Be it known that I, CHARLES WEIS, a citizen of the United States, residing at Lansdale, in the county of Montgomery and State of Pennsylvania, have invented new and useful Improvements in Mail Boxes, of which the following is a specification.

This invention relates to mail boxes and mail bags or containers therefor in which the contents of said mail box are delivered to a bag or container through an automatically opened and automatically closed hinged bottom of said box when the bag or container which is provided with a top frame is projected or pushed into receiving position thereunder.

Among other objects this invention aims to provide a mail box having a hinged bottom which is adapted to normally retain and lock said bottom in closed position with relation to the box body, said bottom being adapted to unlock and permit the hinged part thereof to swing open and automatically deliver or drop the contents of said mail box into a mail bag or container when the top or frame of said mail bag or container is projected or pushed into receiving position under the mail box. At the same time the insertion of the mail bag or container under the mail box unlocks and opens the bag ready to receive the contents of the box and automatically closes and locks the hinged bottom of said mail box and the top of a bag or container when the latter is withdrawn from receiving position with reference to said mail box.

Another object of this invention is to provide a mail box of the type above referred to characterized by means for indicating the time of the next collection of mail from the box and means for automatically unlocking this indicating means upon the opening of the box so that the indicator may be set for the next collection and automatically locked in set position upon the closing of the box.

With the foregoing and other objects in view this invention consists essentially in the novel features of construction, combinations and arrangements of parts hereinafter fully described and more specifically defined by the appended claims.

In the further disclosure of the invention reference is to be had to the accompanying sheets of explanatory drawings constituting

a part of this specification and in which like characters of reference designate the same or corresponding parts in all the views.

Figure 1 is a front elevation of the mail box with the frame and mail bag in receiving position thereunder, part of said bag being broken away for ease in illustration.

Figure 2 is a side elevation partly in section taken substantially on the line 2—2 in Figure 1, and looking in the direction of the arrows, said figure illustrating the top frame of the mail bag and showing the bag frame as attached to the box with the means for locking and mounting the mail bag as well as the means on the frame for actuating the box unlocking and locking mechanism.

Figure 3 is a side elevation of the mail box and mail bag with the top frame of the bag in receiving position and showing the position of some of the co-operating parts on the frame and box when said box is unlocked to discharge its contents.

Figure 4 is a bottom plan view of the mail bag carrying frame and illustrating the means on which said mail bag is mounted as well as the means for attaching the frame to the mail box to unlock the bag, said frame being shown in locked position without the bag attached.

Figure 5 is a vertical cross sectional view taken substantially on the line 5—5 in Figure 3 and looking in the direction of the arrows thereon, said figures showing the interior of the box, the bag carrying frame being removed and the box bottom closed; some of the interior box locking means not being shown for convenience in illustration.

Figure 6 is a vertical section taken substantially on the line 6—6 in Figure 1 and looking in the direction of the arrows thereon, said figures showing a portion of the interior of the box with the mail bag removed and the box bottom closed as well as illustrating the indicator locking device and some of the box bottom locking and controlling means.

Figure 7 is a sectional view of the front of the lower portion of the mail box with the mail bag frame attached, said view being taken substantially on the line 7—7 in Figure 2, and looking in the direction of the arrow thereon; the mail bag proper not being shown in its frame thus indicating the relation of some of the co-operating means.

on the mail box and mail bag frame for unlocking said bag and attaching the frame to and carrying it on the mail box.

Figure 8 is an elevation in detail of the mail box bottom locking mechanisms on the opposite inner sides of said mail box with one side of the casing containing this mechanism removed and showing the relation of the lock members when the bottom is closed and locked, the dotted lines indicating the position of the locking parts when in the open position.

Figure 9 is a plan view of the mechanism shown in Figure 8 and indicating the disposition of the parts within and on the casing, said casing being shown in cross section; and,

Figure 10 is an enlarged view in elevation of the latch members shown in Figures 8 and 9 with the inset which permits the unlocking of one of the other co-operating sliding lock members enclosed in the casing.

Referring more particularly to the drawings, a substantially rectangularly shaped box-body 1 is provided with hinged bottom or fall down doors 2 that are adapted to be actuated by a sliding frame 3 engaging the side members or guides 4 arranged on the lower portions of the opposite outer sides of the box-body. The sliding frame 3 is provided with supporting rods 5, adapted to carry by rings or any other suitable means a bag or container 6 for receiving the mail or contents of the box. Within the box-body 1 there is provided a chute or funnel-like device 7 for guiding the mail in its delivery from the box, the mail being received into the box through an aperture or opening 8 near the top portion of one side of the box. The front face of the box is provided with an indicating device 9, to be operated manually by the mail collector, to indicate the time of next collection of mail, and it is encased behind a face or dial 10 hinged to the front of the box-body and is locked in closed position by a latch or plunger 13 slidably carried on the inner side of the front of the box-body and actuated by the swinging open or shutting of one hinged bottom portion of the box. The front edge 14 of the lower portion of the box-body 1 is provided with a series of teeth or projections 15 substantially perpendicular to the edge 14. The frame 3 is provided with

a sliding lock member 16 carried on said frame which has a box-like formation and is provided with a series of openings or slots 17 similar in number, shape and position to the teeth or projections 15 on the box and they are adapted to receive said teeth therein. The teeth or projections 15 entering the slots 17 engage a series of spring actuated and controlled latches 18, registering in or over said slots 17, said latches 18 being mounted within said box-like member with

one of their ends 19 rigid and their other end free to oscillate upwardly and downwardly. The opposite sides of the sliding frame 3 are provided with runners 20 to slidably carry the lock member 16 between said opposite sides of said frame and form a channel guiding the travel of said sliding lock member 16. Placed substantially beneath said runners 20 are supporting or carrying rods 5 mounted at one end in a cross member 21 of the frame and their other ends being held in rigid relation to the frame and beneath said rod by supporting brackets 22, said rods 5 being adapted to carry a mail bag or container 6 thereon so slidably. Rings 23 or other suitable means engaging said rods 5 and the bag or container 6 are provided to hold said bag or container in operative relation on the frame. The opposite sides or top edges of bag or container that are not attached to the rings 23 on the rods 5 are attached fixedly to the cross members 21 of the frame and to a depending extension 24 of and beneath the bottom of the sliding lock member 16 so that the edge of the bag 6 attached to the cross member 21 is held fixed to said frame; the opposite edge of the bag being attached to the extension 24 beneath the cross member 21 is carried forward or backward with the movement of the sliding lock member 16 and by this means, the bag is opened or shut by the movement of the lock member. The cross member 21 is provided with a series of slots or openings 25 on a rearwardly extended portion, which are adapted to receive teeth or projections 26 extending from within the box-like portion of the sliding lock member 16 through openings 27, and engage the slots or openings 25 and by means of springs 28 operating upon said teeth or projections 26 within said box-like member to lock said sliding member 16 to said cross member 21 of said frame and thereby lock the bag or container 6 in its closed position.

Upon the opposite side longitudinal members of the frame 3 and on the upper surface of said members is fixed a cam 29 which is so placed and of such shape that the forward ends and upper surfaces of said cams will engage and actuate a plurality of latches arranged in co-operative relation therewith in a case 30 on the opposed inner faces of the mail box 1.

Referring now to the mail box and its drop bottom doors 2, said doors are hinged on a series of hinges 31 arranged internally of the box-body in such a manner that when said doors are not held in closed locked position they will simultaneously swing downwardly open by their own weight or the force of gravity and thus deliver the contents of the box into the mail bag 6 which to cause such dropping must at that time be placed in operative relation thereunder.

In my mail box as shown in the accompanying drawings I have provided a bottom closure comprising two doors 2, 2' meeting substantially in the middle section of the mail box bottom, but it is evident that I may construct the box with a single door hinged to one side of said box only and effect the same discharge of its contents by the operation of applying the mail bag frame thereunder. In this double door construction I have provided a link connection 32 controlling the simultaneous dropping and lifting of the doors 2, 2'. The link 32 is pivotally mounted at one end to a bracket 33 which is carried upon the inner face of one door 2—for example—while its other end is pivotally mounted to a bracket or bearing 34 which is oppositely carried on the inner face of the co-operating bottom door. Oppositely arranged on the inner face of one of the doors 2, 2' is a pair of catches 35 which are adapted to be engaged by a latch lever 36—Figure 9—which is mounted on a bearing 37 outside of the case 30 in such a manner as to be free to oscillate to a limited degree and engage the catch members 35 or be disengaged therefrom. This bearing 37 is a stud, bolt or other similar means affixed to the case 30 and extending outwardly therefrom but within the inner body of the box.

In the casing 30 there is contained rocking and sliding members that control an operation of the latch lever 36 and incidentally the locking and unlocking of the box bottom. Rockably mounted on a stud 38 is the latch member 39 normally held when the box bottom is locked in lowered position as shown in solid lines in Figure 8 by means of a spring 40, which spring is mounted on a post 41 carried within the frame 30 so that the outer end of said spring contacts with the latch member 39 near its free end to hold the same in the position aforementioned. This latch member 39 carries an extended arm or member 42 which projects through an opening 43—Figure 3—in the side of the casing 30 and through an opening in the body of the mail box so that the cam 29 aforementioned may engage said arm 42 and operate said latch member 38 when said cam 29 assumes a position in contact therewith. Slidably mounted against the one face of the latch member 39 and supported on a bent-in face or edge of the box member 30 and guided and limited in movement by the stud 38 is a dog carrying member 44. This dog carrying member 44 is provided on its opposite side with extended arms or dogs 45, 46. The arm or dog 45 extends outwardly through an opening 47—Figure 3—in the casing 30 in such position and extent as to be engaged by the end 48 of the cam 29 when the frame 3 is placed in position under the box to open the bottom doors 2, 2' thereof. The arm or dog 46 extends through an opening 49 in the casing 30 toward the interior of the box in such position and extent as to normally lie in easy contact with the arm of the latch lever 36 and act as a stop therefor and as a means to actuate said latch lever 36 and disengage it from locking position with the catches 35 when the end 48 of the cam 29 abuts against the dog 45 and thereby moves both the dogs 45, 46 and permits the box bottoms 2, 2' to be released and opened. The dog carrying member 44 is held in position by the contact of a spring held upon a post provided for mounting the same within the casing 30.

The sliding movement of the dog carrying member 44 is limited by a stop 38 working in a slot 50 near one end of the body of the dog carrying member. There is further provided within the casing 30 a substantially Z-shaped latch or plunger 51 which is permitted a substantially vertical movement in said casing 30 and it has an arm 52 projecting outwardly from said casing 30 through an opening 53 while its upper end is engaged by a spring 51' provided within said casing, the other end of said spring 51' being mounted on a stud member, said spring 51' being adapted to normally hold said plunger 51 in a depressed position when the box bottoms 2, 2' are closed and locked. The lower portion of the main body portion of the plunger 51 is provided with an inset portion 54 and the outwardly extending portion 52 has one edge beveled. The outwardly extended portion 52 of the plunger 51 is so positioned that when the frame carrying the mail bag is slid forward into engagement with the mail box so that the cam 29 is about to engage the dog 45 and the post or stud 42, the end 55 of the frame will contact with and lift said extended arm 52 of said plunger 51 and thereby raise said plunger, and in so doing will lift the inset portion 54 of said plunger upwardly to such an extent that the sliding dog carrying member 44 will be unlocked and free to move upon the stud or stop 38. When this is done, the sliding and locking member within the casing 30 will assume the position shown by dotted lines—in Figure 8—and the box will be at that time unlocked. The latch lever 36 which is mounted within the mail box, but on the outer side of the casing 30 is provided with a pin or stud 56 intermediate its ends which extends within the casing 30 and is engaged by one end of a spring 57 which is mounted at its other end on a stud or post 58 in the interior of said casing 30, the spring 57 acting on the post 56 of the latch lever 36 normally holds said latch lever in engagement with the catches 35 and locks the box bottoms closed. When the frame has been

mounted upon the guides 4 of the mail box open. The indicator having been reset be- and pushed forwardly, the first operation is before the withdrawal of the frame, the frame for the ends 55 of the opposite sides of said is then withdrawn, the bottom doors closed, frame to contact with the plunger 51 and, and presuming the dial to have been closed, lift the same. The cam 29 then is after all the bottom doors force the plunger 13 again 70, slightly forward movement of the frame into engagement with the opening 62 and the engagement with the post 42 and lifting the dial is locked. The door 2 is provided with a rocking member 39, as the forward move- a section 2' that is somewhat dropped below- ment takes place and at the same time, or the level of the hinge portion. This portion 10, immediately subsequent, the end 48 of the 2' is constructed in the door so that after the 75 cam 29 contacts with the dog 45, The plunger, collection has been made and the frame is 15, er, 51 having been lifted, the dog member 44 being withdrawn, the door 2 will thereby is free to move within the casing 38 and sooner contact with the cross end member, the rocking members 39 having been lifted of the frame and will sooner close and lock, 20, by the cam 29 also frees the member 44 for the box bottoms. movement while the abutment of the end 48. The funnel, or guide portion 7, provided 25, of the cam 29, against the dog 45, moves the in the interior of the box is for the pur- 30, 35, 40, 45, 50, 55, 60, 65, 70, 75, 80, 85, 90, 95, 100, 105, 110, 115, 120, 125, 130, 135, 140, 145, 150, 155, 160, 165, 170, 175, 180, 185, 190, 195, 200, 205, 210, 215, 220, 225, 230, 235, 240, 245, 250, 255, 260, 265, 270, 275, 280, 285, 290, 295, 300, 305, 310, 315, 320, 325, 330, 335, 340, 345, 350, 355, 360, 365, 370, 375, 380, 385, 390, 395, 400, 405, 410, 415, 420, 425, 430, 435, 440, 445, 450, 455, 460, 465, 470, 475, 480, 485, 490, 495, 500, 505, 510, 515, 520, 525, 530, 535, 540, 545, 550, 555, 560, 565, 570, 575, 580, 585, 590, 595, 600, 605, 610, 615, 620, 625, 630, 635, 640, 645, 650, 655, 660, 665, 670, 675, 680, 685, 690, 695, 700, 705, 710, 715, 720, 725, 730, 735, 740, 745, 750, 755, 760, 765, 770, 775, 780, 785, 790, 795, 800, 805, 810, 815, 820, 825, 830, 835, 840, 845, 850, 855, 860, 865, 870, 875, 880, 885, 890, 895, 900, 905, 910, 915, 920, 925, 930, 935, 940, 945, 950, 955, 960, 965, 970, 975, 980, 985, 990, 995, 1000, 1005, 1010, 1015, 1020, 1025, 1030, 1035, 1040, 1045, 1050, 1055, 1060, 1065, 1070, 1075, 1080, 1085, 1090, 1095, 1100, 1105, 1110, 1115, 1120, 1125, 1130, 1135, 1140, 1145, 1150, 1155, 1160, 1165, 1170, 1175, 1180, 1185, 1190, 1195, 1200, 1205, 1210, 1215, 1220, 1225, 1230, 1235, 1240, 1245, 1250, 1255, 1260, 1265, 1270, 1275, 1280, 1285, 1290, 1295, 1300, 1305, 1310, 1315, 1320, 1325, 1330, 1335, 1340, 1345, 1350, 1355, 1360, 1365, 1370, 1375, 1380, 1385, 1390, 1395, 1400, 1405, 1410, 1415, 1420, 1425, 1430, 1435, 1440, 1445, 1450, 1455, 1460, 1465, 1470, 1475, 1480, 1485, 1490, 1495, 1500, 1505, 1510, 1515, 1520, 1525, 1530, 1535, 1540, 1545, 1550, 1555, 1560, 1565, 1570, 1575, 1580, 1585, 1590, 1595, 1600, 1605, 1610, 1615, 1620, 1625, 1630, 1635, 1640, 1645, 1650, 1655, 1660, 1665, 1670, 1675, 1680, 1685, 1690, 1695, 1700, 1705, 1710, 1715, 1720, 1725, 1730, 1735, 1740, 1745, 1750, 1755, 1760, 1765, 1770, 1775, 1780, 1785, 1790, 1795, 1800, 1805, 1810, 1815, 1820, 1825, 1830, 1835, 1840, 1845, 1850, 1855, 1860, 1865, 1870, 1875, 1880, 1885, 1890, 1895, 1900, 1905, 1910, 1915, 1920, 1925, 1930, 1935, 1940, 1945, 1950, 1955, 1960, 1965, 1970, 1975, 1980, 1985, 1990, 1995, 2000, 2005, 2010, 2015, 2020, 2025, 2030, 2035, 2040, 2045, 2050, 2055, 2060, 2065, 2070, 2075, 2080, 2085, 2090, 2095, 2100, 2105, 2110, 2115, 2120, 2125, 2130, 2135, 2140, 2145, 2150, 2155, 2160, 2165, 2170, 2175, 2180, 2185, 2190, 2195, 2200, 2205, 2210, 2215, 2220, 2225, 2230, 2235, 2240, 2245, 2250, 2255, 2260, 2265, 2270, 2275, 2280, 2285, 2290, 2295, 2300, 2305, 2310, 2315, 2320, 2325, 2330, 2335, 2340, 2345, 2350, 2355, 2360, 2365, 2370, 2375, 2380, 2385, 2390, 2395, 2400, 2405, 2410, 2415, 2420, 2425, 2430, 2435, 2440, 2445, 2450, 2455, 2460, 2465, 2470, 2475, 2480, 2485, 2490, 2495, 2500, 2505, 2510, 2515, 2520, 2525, 2530, 2535, 2540, 2545, 2550, 2555, 2560, 2565, 2570, 2575, 2580, 2585, 2590, 2595, 2600, 2605, 2610, 2615, 2620, 2625, 2630, 2635, 2640, 2645, 2650, 2655, 2660, 2665, 2670, 2675, 2680, 2685, 2690, 2695, 2700, 2705, 2710, 2715, 2720, 2725, 2730, 2735, 2740, 2745, 2750, 2755, 2760, 2765, 2770, 2775, 2780, 2785, 2790, 2795, 2800, 2805, 2810, 2815, 2820, 2825, 2830, 2835, 2840, 2845, 2850, 2855, 2860, 2865, 2870, 2875, 2880, 2885, 2890, 2895, 2900, 2905, 2910, 2915, 2920, 2925, 2930, 2935, 2940, 2945, 2950, 2955, 2960, 2965, 2970, 2975, 2980, 2985, 2990, 2995, 3000, 3005, 3010, 3015, 3020, 3025, 3030, 3035, 3040, 3045, 3050, 3055, 3060, 3065, 3070, 3075, 3080, 3085, 3090, 3095, 3100, 3105, 3110, 3115, 3120, 3125, 3130, 3135, 3140, 3145, 3150, 3155, 3160, 3165, 3170, 3175, 3180, 3185, 3190, 3195, 3200, 3205, 3210, 3215, 3220, 3225, 3230, 4885, 4890, 4895, 4900, 4905, 4910, 4915, 4920, 4925, 4930, 4935, 4940, 4945, 4950, 4955, 4960, 4965, 4970, 4975, 4980, 4985, 4990, 4995, 5000, 5005, 5010, 5015, 5020, 5025, 5030, 5035, 5040, 5045, 5050, 5055, 5060, 5065, 5070, 5075, 5080, 5085, 5090, 5095, 5100, 5105, 5110, 5115, 5120, 5125, 5130, 5135, 5140, 5145, 5150, 5155, 5160, 5165, 5170, 5175, 5180, 5185, 5190, 5195, 5200, 5205, 5210, 5215, 5220, 5225, 5230, 5235, 5240, 5245, 5250, 5255, 5260, 5265, 5270, 5275, 5280, 5285, 5290, 5295, 5300, 5305, 5310, 5315, 5320, 5325, 5330, 5335, 5340, 5345, 5350, 5355, 5360, 5365, 5370, 5375, 5380, 5385, 5390, 5395, 5400, 5405, 5410, 5415, 5420, 5425, 5430, 5435, 5440, 5445, 5450, 5455, 5460, 5465, 5470, 5475, 5480, 5485, 5490, 5495, 5500, 5505, 5510, 5515, 5520, 5525, 5530, 5535, 5540, 5545, 5550, 5555, 5560, 5565, 5570, 5575, 5580, 5585, 5590, 5595, 5600, 5605, 5610, 5615, 5620, 5625, 5630, 5635, 5640, 5645, 5650, 5655, 5660, 5665, 5670, 5675, 5680, 5685, 5690, 5695, 5700, 5705, 5710, 5715, 5720, 5725, 5730, 5735, 5740, 5745, 5750, 5755, 5760, 5765, 5770, 5775, 5780, 5785, 5790, 5795, 5800, 5805, 5810, 5815, 5820, 5825, 5830, 5835, 5840, 5845, 5850, 5855, 5860, 5865, 5870, 5875, 5880, 5885, 5890, 5895, 5900, 5905, 5910, 5915, 5920, 5925, 5930, 5935, 5940, 5945, 5950, 5955, 5960, 5965, 5970, 5975, 5980, 5985, 5990, 5995, 6000, 6005, 6010, 6015, 6020, 6025, 6030, 6035, 6040, 6045, 6050, 6055, 6060, 6065, 6070, 6075, 6080, 6085, 6090, 6095, 6100, 6105, 6110, 6115, 6120, 6125, 6130, 6135, 6140, 6145, 6150, 6155, 6160, 6165, 6170, 6175, 6180, 6185, 6190, 6195, 6200, 6205, 6210, 6215, 6220, 6225, 6230, 6235, 6240, 6245, 6250, 6255, 6260, 6265, 6270, 6275, 6280, 6285, 6290, 6295, 6300, 6305, 6310, 6315, 6320, 6325, 6330, 6335, 6340, 6345, 6350, 6355, 6360, 6365, 6370, 6375, 6380, 6385, 6390, 6395, 6400, 6405, 6410, 6415, 6420, 6425, 6430, 6435, 6440, 6445, 6450, 6455, 6460, 6465, 6470, 6475, 6480, 6485, 6490, 6495, 6500, 6505, 6510, 6515, 6520, 6525, 6530, 6535, 6540, 6545, 6550, 6555, 6560, 6565, 6570, 6575, 6580, 6585, 6590, 6595, 6600, 6605, 6610, 6615, 6620, 6625, 6630, 6635, 6640, 6645, 6650, 6655, 6660, 6665, 6670, 6675, 6680, 6685, 6690, 6695, 6700, 6705, 6710, 6715, 6720, 6725, 6730, 6735, 6740, 6745, 6750, 6755, 6760, 6765, 6770, 6775, 6780, 6785, 6790, 6795, 6800, 6805, 6810, 6815, 6820, 6825, 6830, 6835, 6840, 6845, 6850, 6855, 6860, 6865, 6870, 6875, 6880, 6885, 6890, 6895, 6900, 6905, 6910, 6915, 6920, 6925, 6930, 6935, 6940, 6945, 6950, 6955, 6960, 6965, 6970, 6975, 6980, 6985, 6990, 6995, 7000, 7005, 7010, 7015, 7020, 7025, 7030, 7035, 7040, 7045, 7050, 7055, 7060, 7065, 7070, 7075, 7080, 7085, 7090, 7095, 7100, 7105, 7110, 7115, 7120, 7125, 7130, 7135, 7140, 7145, 7150, 7155, 7160, 7165, 7170, 7175, 7180, 7185, 7190, 7195, 7200, 7205, 7210, 7215, 7220, 7225, 7230, 7235, 7240, 7245, 7250, 7255, 7260, 7265, 7270, 7275, 7280, 7285, 7290, 7295, 7300, 7305, 7310, 7315, 7320, 7325, 7330, 7335, 7340, 7345, 7350, 7355, 7360, 7365, 7370, 7375, 7380, 7385, 7390, 7395, 7400, 7405, 7410, 7415, 7420, 7425, 7430, 7435, 7440, 7445, 7450, 7455, 7460, 7465, 7470, 7475, 7480, 7485, 7490, 7495, 7500, 7505, 7510, 7515, 7520, 7525, 7530, 7535, 7540, 7545, 7550, 7555, 7560, 7565, 7570, 7575, 7580, 7585, 7590, 7595, 7600, 7605, 7610, 7615, 7620, 7625, 7630, 7635, 7640, 7645, 7650, 7655, 7660, 7665, 7670, 7675, 7680, 7685, 7690, 7695, 7700, 7705, 7710, 7715, 7720, 7725, 7730, 7735, 7740, 7745, 7750, 7755, 7760, 7765, 7770, 7775, 7780, 7785, 7790, 7795, 7800, 7805, 7810, 7815, 7820, 7825, 7830, 7835, 7840, 7845, 7850, 7855, 7860, 7865, 7870, 7875, 7880, 7885, 7890, 7895, 7900, 7905, 7910, 7915, 7920, 7925, 7930, 7935, 7940, 7945, 7950, 7955, 7960, 7965, 7970, 7975, 7980, 7985, 7990, 7995, 8000, 8005, 8010, 8015, 8020, 8025, 8030, 8035, 8040, 8045, 8050, 8055, 8060, 8065, 8070, 8075, 8080, 8085, 8090, 8095, 8100, 8105, 8110, 8115, 8120, 8125, 8130, 8135, 8140, 8145, 8150, 8155, 8160, 8165, 8170, 8175, 8180, 8185, 8190, 8195, 8200, 8205, 8210, 8215, 8220, 8225, 8230, 8235, 8240, 8245, 8250, 8255, 8260, 8265, 8270, 8275, 8280, 8285, 8290, 8295, 8300, 8305, 8310, 8315, 8320, 8325, 8330, 8335, 8340, 8345, 8350, 8355, 8360, 8365, 8370, 8375, 8380, 8385, 8390, 8395, 8400, 8405, 8410, 8415, 8420, 8425, 8430, 8435, 8440, 8445, 8450, 8455, 8460, 8465, 8470, 8475, 8480, 8485, 8490, 8495, 8500, 8505, 8510, 8515, 8520, 8525, 8530, 8535, 8540, 8545, 8550, 8555, 8560, 8565, 8570, 8575, 8580, 8585, 8590, 8595, 8600, 8605, 8610, 8615, 8620, 8625, 8630, 8635, 8640, 8645, 8650, 8655, 8660, 8665, 8670, 8675, 8680, 8685, 8690, 8695, 8700, 8705, 8710, 8715, 8720, 8725, 8730, 8735, 8740, 8745, 8750, 8755, 8760, 8765, 8770, 8775, 8780, 8785, 8790, 8795, 8800, 8805, 8810, 8815, 8820, 8825, 8830, 8835, 8840, 8845, 8850, 8855, 8860, 8865, 8870, 8875, 8880, 8885, 8890, 8895, 8900, 8905, 8910, 8915, 8920, 8925, 8930, 8935, 8940, 8945, 8950, 8955, 8960, 8965, 8970, 8975, 8980, 8985, 8990, 8995, 9000, 9005, 9010, 9015, 9020, 9025, 9030, 9035, 9040, 9045, 9050, 9055, 9060, 9065, 9070, 9075, 9080, 9085, 9090, 9095, 9100, 9105, 9110, 9115, 9120, 9125, 9130, 9135, 9140, 9145, 9150, 9155, 9160, 9165, 9170, 9175, 9180, 9185, 9190, 9195, 9200, 9205, 9210, 9215, 9220, 9225, 9230, 9235, 9240, 9245, 9250, 9255, 9260, 9265, 9270, 9275, 9280, 9285, 9290, 9295, 9300, 9305, 9310, 9315, 932

hinged to the face of said box-body, an arm extending into said box-body integral with said cover, a pin or plunger slidably mounted within said box body adapted to be supported by said fall down doors when said doors are closed and engage the extended arm of said dial cover to lock same closed and to be disengaged from said arm when said doors are opened.

10 2. In a mail box, a box-body, fall down doors hinged therein, a dial on the outer face of said box-body, a cover hinged to the face of the box-body, an arm extending into said box-body, a plunger slidably mounted within said box-body and adapted to be supported by said doors when said doors are closed and engage the extended arm of said dial cover to lock the same closed and to be disengaged from said arm when said doors are opened.

15 3. In a mail box, a box-body, a front extended edge thereon, opposite guide members laterally extending from said box-body on opposite sides thereof, fall-down doors mounted in said box-body, latch means to hold said doors normally closed, means slideable on said extended guides to actuate said latch member and open or close said doors,

a dial on the outer face of the box-body, a cover hinged to the face of the box-body, 30 an arm on said cover and extending into the box-body, a plunger slidably within the box-body and adapted to be supported by said fall-down doors when the doors are closed and engage said arm to lock the same 35 closed, and to be disengaged from said arm when said doors are open.

4. In a mail box, a box body, a bag carrying member slideable in the box body, a bag carried by said member, means for normally locking said bag closed, fall down doors hinged in said box body, a dial on the outer face of said box body, a lid or cover hinged to the face of the box body, an arm extending into said box body integral with 40 said cover, a pin or plunger slidably mounted within said box body adapted to be supported by said fall down doors when said doors are closed and engage the extended arm of said dial cover to lock said door 45 closed and to be disengaged from said arm when said doors are open.

In testimony whereof I affix my signature.

CHARLES WEIS.
